UNITED STATES PATENT OFFICE.

ROY CROSS, OF KANSAS CITY, MISSOURI, ASSIGNOR TO GASOLINE PRODUCTS COMPANY,
OF NEW YORK, N. Y., A CORPORATION OF NEW YORK.

PROCESS AND APPARATUS FOR CONVERTING PETROLEUM HYDROCARBONS.

Application filed October 29, 1923. Serial No. 671,355.

This invention relates to improvements in a process and apparatus for converting petroleum hydrocarbons, and refers more particularly to a process in which oils are treated under temperature and pressure conditions to effect a conversion, whereby they have an increased amount of oils of a lower molecular weight and lower boiling point.

Among the salient objects of the invention are to provide a process for producing gasoline-like bodies or light hydrocarbons having the characteristics of gasoline and adapted to be used as motor fuel; to provide a process which may be operated continuously, and one in which the hydrocarbons, during the cracking reaction, are kept in close association with a considerable body of highly heated oil whereby a more complete and satisfactory conversion takes place; to provide a process in which the carbon containing oils are kept separate from the oils introduced to the system, although advantage is taken of the heat in the body undergoing conversion, to preheat the incoming hydrocarbons; and, to provide an apparatus for carrying out this process.

In the drawings:

Fig. 1 is a diagrammatic side elevational view of the apparatus with parts broken away from the separate stages to disclose the interior construction.

Fig. 2 is an enlarged detailed sectional view taken of the rotary scraper element positioned in the conversion chamber.

Referring to the drawings, the apparatus consists of a heating coil 1, positioned in the furnace 2, which is preferably heated by means of gas burners such as that shown at 3. 4 is a conversion chamber positioned above the furnace and connected by lines 5 and 6 to the heating coil. At 7 is shown a preheater which has communication with the conversion chamber through the lines 8 and 9. Above the preheater is positioned a dephlegmating column 10, from the top of which is a vapor line 11 communicating with the coil 12 positioned in the water-cooled condenser box 13. The discharge end of the condensing coil has connection, through a pipe 14, with a gas separators 15. The latter is equipped with a liquid draw-off line 16 controlled by a valve 17, a pressure relief pipe 18 controlled by a valve 19 and return line 20 connected to the gas burners 3.

Explaining now, briefly, the method in which the oil is treated, such hydrocarbons as are normally used as a charging stock for cracking system, are introduced through the apparatus from any convenient source 60 through the line 21 and are forced, by means of the pump 22, through the charging line 23 controlled by a valve 24 to an enlarged inlet 25 which has communication with a preheating tank 7. Sufficient oil is charged 65 to the system to fill the preheater to a height approximately that shown in the drawing. This chamber is in free communication with the conversion chamber 4 through the lines 9 and 8, therefore the oil will seek its level 70 in the chamber 4, completely filling the heating coil 6. In this connection, it will be noted that in the conversion chamber 4 is positioned a partition wall 26, which causes the oil introduced to the system to pass from the pool 4^a through the heating coil 1, and thence into the pool 4^b, thus maintaining a 75 continuous circulation through the heating coil and isolating the oil undergoing conversion in the pool 4^b where the carbon deposition will take place. Normally, the circulation 80 will be sufficiently rapid, due to the convection current set up by the heat of the furnace and the liquid head maintained in the preheater. If, however, this circulation is 85 found to be too sluggish and produces carbon deposition in the heating coil, a pump 90 may be inserted in the line 5 to assure adequate velocity of the oil through the heating zone.

As stated, the oil is introduced to the preheater, and from this stage finds its way through the line 9 and pool 4^a into the heating coil through the line 5. In the heating coil it is raised to a conversion temperature 95 and is discharged through the line 6 into the pool 4^b where it is collected in a substantial body and where the major portion of the conversion takes place. During the conversion of the oil, there is considerable 100 carbon deposition which will collect along the bottom of the chamber 4 in the pool 4^b. This carbon is kept in a suspended condition by the action of the scraper element 27 which is rotatable upon the discharge line 28, the 105 latter acting as a shaft for the scraper element. This rotation is effected by means of a spiral rotator or turbine arrangement 29 fixedly attached to the scraper and mounted 110 in the open end of the discharge line shown

in detail in Fig. 2. The rotation is produced by the oil being discharged from the system through the line 28, acting upon the spiral baffle members in the rotator 29 and causing an agitation and turbulency in the pool 4^b, thus scraping any carbon tending to accumulate on the bottom of the chamber from the shell and producing a constant motion to the oil body which will tend to keep the carbon parts in suspension. The carbon laden residual material is discharged through the line 28, which extends substantially the entire length of the conversion and preheating stages, thus, in its travel, simultaneously supplying heat to the oil which is introduced to the system and cooling the residual material, being discharged through the draw-off line 28, which is connected to any convenient storage, or to a coking plant, for re-treatment of the residual hydrocarbon products. A valve 30 is interposed in the line 28. The conversion chamber is equipped with a pressure gauge 31 and a thermo couple 32. The vapors, evolved in the reaction or conversion chamber, pass over the partition wall 26 through the line 8 and are brought into intimate contact with the relatively cooler incoming oil maintained in a body in the chamber 7. Radiating elements 7^a, in the form of perforated plates, are positioned in the path of the vapors and are partially immersed in the oil, thereby effecting a better heat transfer to the liquid oil body and more effectively refluxing the vapors. In their travel, the vapors are subjected to a refluxing action whereby certain of the heavier products will be separated out. From the chamber 7 the vapors rise through the line 33 and pass up through the dephlegmator 10 wherein their travel is obstructed by perforated pans, the construction effecting a further refluxing action to the vapors. Subsequent to this latter dephlegmation, the still uncondensed vapors pass off and are subjected to a final condensing action in the coil 12, after which they are discharged into the gas separator in the form of liquid distillate. From the gas separator the distillate is drawn off and directed to storage, while the gas may be returned through the line 20 and utilized as fuel in the furnace or removed through the pipe 18 to storage. The valve in the pipe 18 serves as a control for the pressure maintained upon the system.

For ascertaining the pressures in the separate stages of the system, the conversion chamber and preheater are equipped with pressure gauges 31, and for determining the temperatures, thermocouples 32 are positioned on both the conversion chamber and preheating units.

The novelty in the invention lies principally in the efficient utilization of the heat of the system together with the maintaining

of the carbon in a suspended condition by an automatically operated agitator or scraper; the maintaining of separate pools of oil in the conversion and charging pools respectively substantially in free communication, as far as the vapor spaces are concerned, while the liquids in the pools are kept separate and prevented from mixing; a means by which the vaporized hydrocarbons may be directed from the conversion stage into, or through, the preheating or charging pool wherein the vapors are subjected to a refluxing or condensing action while the oil in the charging pool is preheated. The unvaporized liquid in the conversion pool is eliminated and its energy utilized to retard the carbon deposition in the conversion or reaction chamber.

A further variation, which may produce more efficient dephlegmation, would be to connect up the vapor transfer line 8 with a perforated pipe immersed in the charging pool maintained in the chamber 7 so that the vapors from the conversion stage would be percolated through the body of the oil in place of their passing over the surface of the oil, as is shown in the drawings.

The purpose of maintaining a definite separation or partition between the oils in the separate pools is to prevent the mixing of the liquid hydrocarbons which would produce a contamination of the oil in the charging pool with objectionable free-carbon separated out in the conversion pool and suspended in the oil in the latter pool. This contamination would be objectionable to the oil in the charging pool, prior to its circulation through the heating coil, as deposition in the heating stage would promote the production of hot spots and a consequential deterioration of the tubes in the heating zone. By maintaining them separate with free vapor communication, advantage may be taken of the heat of the conversion pool while the objectionable features resulting from the mixing of the liquids is eliminated. The agitation and scraper element, automatically operated by the unvaporized products withdrawn from the system, tends to maintain the conversion stage in a relative turbulent condition, promoting vaporization and retarding the carbon deposition or accumulation in this latter stage. By running the discharge line substantially throughout the length of the two pools, the heat in this residual material is utilized to preheat the oil and serves to cool the drawn-off material.

The temperatures and pressures, maintained upon the system, will vary according to the oil treated. It is desirable, under certain conditions, with the treating of kerosene and lighter refractory oils, to maintain comparatively high temperatures and pressures, while with oils more easily cracked, temperatures and pressures may be reduced

commensurate with conditions necessary to produce the most desirable conversion.

In cracking Mid-Continent gas oil ranging from 32° to 35° Baumé, a satisfactory 5 yield of high-grade distillate was obtained by treatment of the oil under temperatures ranging from 600° to 900° F. and pressures of from 200 to 500 pounds.

I claim as my invention:

10 1. A process of producing a turbulent condition in oil undergoing conversion in an oil cracking system, consisting in utilizing the energy made available by the release of pressure in withdrawing liquid products 15 from the system to mechanically agitate the oil body.

20 2. A process for retarding the accumulation of carbon separated from the oil in a cracking system during conversion, consisting in utilizing the energy made available by the release of pressure in withdrawing conversion products from the system to mechanically agitate and maintain the oil in a turbulent condition and retain the separated 25 carbon in suspension in the oil.

30 3. A process for converting petroleum hydrocarbons consisting in charging the oil to an initial stage in which the oil accumulates in a pool, thence through a heating stage and then to a conversion stage, maintaining the liquid products in the initial stage and the conversion stage separate with open vapor communication therebetween passing the evolved vapors from the conversion stage through the initial stage containing the pool of relatively cooler oil, thence to dephlegmating and condensing stages, withdrawing the unvaporized products from the conversion stage and utilizing 35 their energy to produce a turbulent condition of the oil in the conversion stage, and maintaining carbon, separated during the conversion reaction, in a suspended condition.

40 4. In an apparatus for converting petroleum hydrocarbons, the combination with means for maintaining oil in separate pools, of means for circulating the oil from the initial pool through a heating means, thence 45 to a subsequent pool wherein the conversion takes place, a communicating means between the separate pools whereby the vapors evolved in the latter pool are directed to the initial pool, a dephlegmating and condensing means serially connected to the initial pool for treating the hydrocarbon vapors, and means for drawing off the unvaporized products from the conversion pool, said means being adapted to transmit heat from 50 the withdrawn products to the oil in the initial pool.

55 5. A process for retarding the accumulation of carbon separated from the oil in a cracking system during conversion, consisting in utilizing the energy made available 60

by the release of pressure in withdrawing conversion products from the system to mechanically agitate and maintain the oil in a turbulent condition, and the carbon in suspension and the collecting surfaces 70 scraped free of deposited material.

6. In an apparatus for converting petroleum hydrocarbons, the combination with means for maintaining oil in separate pools, of means for circulating the oil from the initial pool through a heating means, thence to a subsequent pool wherein the conversion takes place, a communicating means between the separate pools whereby the vapors evolved in the latter pool are directed to 80 the initial pool, a dephlegmating and condensing means serially connected to the initial pool for treating the hydrocarbon vapors, and means for drawing off the oil from the conversion stage, and means for utilizing the energy of the drawn-off liquids to produce a turbulent condition of the oil in the conversion stage and retard carbon accumulation therein.

7. A process of converting petroleum hydrocarbons, comprising the steps of passing oil successively through a heat exchanger, a heating stage and a reaction or vaporizing stage, maintaining the heat exchanger and vaporizing stage in open vapor communication, passing the evolved vapors from the vaporizing stage through the heat exchanger, thence to refluxing and condensing stages and utilizing the energy made available by the release in pressure in withdrawing liquid products from the system to retard the accumulation by deposition of the separated carbon.

8. A process of converting petroleum hydrocarbons, comprising the steps of passing oil successively through a heat exchanger, a heating stage and a reaction vaporizing stage, maintaining the heat exchanger and vaporizing stage in open vapor communication, passing the evolved vapors from the vaporizing stage through the heat exchanger, thence to refluxing and condensing stages and utilizing the energy made available by the release in pressure in withdrawing liquid products from the system to retard the accumulation by deposition of the separated carbon, and facilitating and promoting the heat transfer between the vapors and liquid in the heat exchanger stage by radiating elements positioned partially in the liquid and vapor spaces.

9. An apparatus of the character described, comprising separate communicating heat exchanger and conversion means, a heating element, means for circulating preheated oil through said heating element to the conversion means, dephlegmating and condensing elements and connections through which the evolved vapors are passed through the heat exchanger thereto, a draw off line from

4 the conversion means adapted to transmit evolved vapors are passed from the conversion means through the heat exchanger heat to the incoming oil.

10. An apparatus of the character described, comprising separate communicating 5 heat exchanger and conversion means, a heating element and means for circulating the preheated oil from the heat exchanger through the heating element to the conversion means, dephlegmating and condens-
10 ing elements and connections whereby the

to said dephlegmating and condensing ele-
ments, and means for using energy made
available by the release in pressure in with-
15 drawing liquid products from the system
to retard accumulation of carbon in the con-
version means.
